SCONCE

Francis P. Brennan, Chicago, Ill.

Application September 16, 1955, Serial No. 37,967

Term of patent 7 years

(Cl. D48—2)

Fig. 1 is a front elevational view of a sconce showing my new design;

Fig. 2 is a top plan view of said sconce; and

Fig. 3 is a fragmentary side elevational view showing the lower part of the sconce.

This application is a continuation-in-part of application Ser. No. D. 33,593, filed December 16, 1954, now co-pending.

Fig. 2.

Fig. 3.

I claim:

The ornamental design for a sconce, as shown.
